UNITED STATES PATENT OFFICE.

ANNA BROHMAN GRIBBLE, OF NEWARK, NEW JERSEY, ASSIGNOR TO W. J. SCOTT CO.,
OF NEWARK, NEW JERSEY, A CORPORATION OF NEW JERSEY.

GARMENT.

1,412,683.

Specification of Letters Patent. Patented Apr. 11, 1922.

Application filed July 14, 1921. Serial No. 484,559.

To all whom it may concern:

Be it known that I, ANNA BROHMAN GRIBBLE, a citizen of the United States, and a resident of Newark, in the county of Essex and 5 State of New Jersey, have invented a new and Improved Garment, of which the following is a full, clear, and exact description.

The invention relates to a combined dress and bloomers, and its object is to provide a 10 new and improved garment more especially designed for children's wear and arranged to permit of quickly and conveniently donning the garment or removing it from the body of the wearer.

15 Another object is to insure the utmost comfort to the wearer and to provide a fine appearance of the garment.

Another object is to provide a desired convenience for sanitary purposes without requiring opening up or removal of the body 20 of the garment.

Another object is to allow of making the garment of comparatively few pieces thus reducing the cost of manufacture to a mini- 25 mum.

With these and other objects in view, the invention consists of certain novel features of construction as hereinafter shown and described and then specifically pointed out in 30 the claims.

A practical embodiment of the invention is represented in the accompanying drawings forming a part of this specification, in which similar characters of reference indicate corresponding parts in all the views.

Figure 1 is a front perspective view of the garment as applied;

Figure 2 is a rear elevation of the garment with a portion of the hem of the dress 40 turned up and with the sanitary flap partly unfastened;

Figure 3 is an enlarged cross section of the garment on the line 3—3 of Figure 2;

Figure 4 is a plan view of the front piece 45 of the body of the garment; and

Figure 5 is a similar view of the back piece of the body of the garment.

The garment in its general construction comprises a dress 10 and bloomers 11, of 50 which the dress 10 is preferably closed at the front and provided at the median line of the back with the usual opening and closing flaps 12 to allow of conveniently donning or removing the garment. The body 55 15 of the dress 10 is provided with a yoke 16

and sleeves 17, and use is preferably made of a sash or belt 18 fixed at the front of the dress and adapted to be tied into a bow 19 at the back of the dress across the closing flaps 12, as plainly shown in Figure 2. The 60 dress may also be trimmed more or less elaborately to provide a more or less expensive garment. The bloomers 11 consist essentially of a body 20, legs 21 and a sanitary flap 22 at the back of the body 20. 65

In the manufacture of the garment, the body 15 of the dress and the bloomers 11 are made of a front piece 25 and a back piece 26, the two pieces being sewed together along the side edges 27, 28 and the bottom edges 70 29, 30 with the exception of the portions 31 and 32 forming the legs 21 (see Figures 4 and 5). The two pieces 25 and 26 after being fastened together have a portion doubled up inwardly and upwardly (see 75 Figure 3) to provide a wide hem 40 at the lower end of the dress. A circumferential row of stitches 41 connect the doubled-up portions with each other at the upper end to define the hem 40 and at the same time 80 attach the upper portion of the body 20 of the bloomers circumferentially to the inner surface of the body 15 of the dress 10. It will be noticed that by this arrangement the desired fullness is given to the body 20 of 85 the bloomer to provide the utmost comfort to the wearer and hence complete freedom in the movement of the wearer's legs is obtained.

The sanitary flap 20 forms an integral 90 part of the back piece 26 and for this purpose the back piece 26 is cut horizontally along a line 45 and vertically along lines 46 extending downward from the ends of the line 45. This line 45 is intersected by the 95 opening or cut 47 for the opening and closing flaps 12 previously mentioned. It will be noticed that by the arrangement described a sanitary opening is formed at the back piece 26 and this opening is intersected by 100 the opening 47 for the opening and closing flaps 12. It will also be noticed that this sanitary opening is below the circumferential row of stitches 41 and the hem 40 is of sufficient height to overlie the sanitary flap 22 105 when the garment is worn and hence the sanitary flap 22 is normally not visible. The usual fastening devices, such as buttons and button holes 50 and 51 are provided for holding the sanitary flap 22 in closed posi- 110

tion, the buttons extending along the body 20 directly below the row of stitches 41, and the buttonholes 51 being located at the upper end of the sanitary flap 22. It will be noticed that by this arrangement the sanitary flap 22 forms an integral part of the back piece 26 and adds comparatively little to the expense of manufacturing the garment. The lower edges of the legs 21 are preferably 10 provided with suitable trimmings 55 to enhance the appearance of the garment.

Ordinarily the sanitary flap 22 is held in closed position by the buttons 50 and buttonholes 51, and in donning or removing 15 the garment it is only necessary to open the flaps 12. When the garment is worn, the sanitary flap 22 can be readily unfastened and swung downward without, however, requiring opening of the flaps 12.

Having thus described my invention I claim as new and desire to secure by Letters Patent:

1. A garment comprising a dress closed at the front and provided at the back along 25 the median line with opening and closing flaps for opening and closing the back, bloomers forming an integral part of the dress and permanently attached circumferentially to the inner surface of the dress 30 intermediate the waist line and the lower edge thereof, said bloomers being provided at the back with a sanitary opening and drop

flap below the said circumferential line of attachment, said opening and closing flaps extending to said sanitary opening, and the 35 free upper edge of said flap concealing the lower united ends of said opening and closing flaps.

2. A garment, comprising a dress and bloomers, the dress being closed at the front 40 and provided along the median line of the back with opening and closing flaps for opening and closing the back, the bloomers having a body and legs, the body of the dress and bloomers being made of a front 45 piece and a back piece fastened together along the sides and the bottom except at the bloomer legs, the said front and back pieces being doubled up, and a row of stitches connecting the upper portion of the 50 doubled-up parts with each other to form a hem at the lower portion of the dress, the said row of stitches permanently attaching the upper portion of the body of the bloomers to the top edge of the hem, the said back 55 piece being provided at the body of the bloomers with a sanitary opening and an integral sanitary drop flap for closing the said opening, and closing devices for closing the sanitary flap immediately below the said 60 row of stitches, the opening of the back of the dress intersecting the drop flap opening at the back of the bloomer body.

ANNA BROHMAN GRIEBIE. [L. S.]
